UNITED STATES PATENT OFFICE.

MORTON C. BLEDSOE AND GERHARDT FREDK. BLUMENKAMP, OF ST. LOUIS, MISSOURI.

TYPE-WRITER.

No. 861,943.

Specification of Letters Patent.

Patented July 30, 1907.

Application filed January 19, 1907. Serial No. 853,124.

To all whom it may concern:

Be it known that we, MORTON C. BLEDSOE and GERHARDT FREDK. BLUMENKAMP, citizens of the United States, residing at St. Louis, in the county of St. Louis 5 City and State of Missouri, have invented new and useful Improvements in Type-Writers, of which the following is a specification.

The invention relates to an improvement in typewriters and particularly to an attachment arranged for 10 ready connection to or disconnection from the typewriter and adapted for movably supporting one or more rolls for service as a paper supply to the typewriter platen.

The main object of the present invention resides in 15 the production of a typewriter attachment carrying one or more rolls of papers and an interposed roll of carbon which are designed in the use of the attachment to be properly fed to the typewriter platen, the construction providing for so mounting the attachment as to insure 20 its travel in exact accordance with the travel of the carriage of the typewriter, whereby the alinement of the paper is maintained accurate and the inconvenience incident to the supplying of the paper to the platen in the ordinary way is entirely avoided.

25 The invention will be described in the following specification, reference being had particularly to the accompanying drawings, in which:—

Figure 1 is a side elevation illustrating the application of our attachment to a typewriter, Fig. 2 is a front 30 elevation of the attachment removed, Fig. 3 is a plan of the base frame of the attachment, Fig. 4 is an enlarged vertical section of the main paper carrier of the attachment, Fig. 5 is a section on line 5—5 of Fig. 4, Fig. 6 is an end elevation of Fig. 4, Fig. 7 is a broken 35 vertical section of one of the frame uprights of the attachment, Fig. 8 is a front elevation of the same, Fig. 9 is a broken vertical sectional view of the same, illustrating the means for securing the sections of the upright in operative relation, Fig. 10 is a broken perspective of the transverse member of the attachment frame.

Referring particularly to the drawings, wherein similar reference numerals indicate like parts throughout the several views, our typewriter attachment comprises a main frame including base blocks 1, preferably of rectangular outline and designed to rest upon the typewriter table or other support 2. Blocks are connected by a transverse frame 3 including spaced side bars 4, which extend in parallel relation from one block to the other and are connected adjacent each end by cross bars 5. At the ends of the bars 4, and at the ends of the cross bars 5, at each end of the transverse frame, are provided depending pins 6, designed to enter openings 7 formed in the upper surface of each base block. Inwardly from the point of attachment to the base blocks

the side bars 4 of the transverse frame are projected 55 downwardly at 8, the extent of the projection approximately equaling the thickness of the base block 1, whereby that portion of the side bars 4 arranged between the inclined portions 8 are adapted to bear directly upon the support 2, thereby providing for a more 60 staple base support. The cross bars 4 are engaged by spaced parallel arranged holding strips 9, having removable connection at 10 with the bars 4, and extending forwardly at a right angle to said bars. Each of the bars 9 is formed with sockets 11 and 12, the former being 65 arranged at the end of the bar and the latter about midway its length. Sockets are thus provided for the reception of the feet 13 of the typewriter 14, whereby the main frame of the attachment is held in proper operative relation to the typewriter when in use. 70

The base plates 1 are centrally formed with sockets 15 designed respectively to receive end standards 16 and 17 for the support of the paper rolls, as hereinafter described. The standard 16 is formed on its relatively inner face with a series of longitudinally disposed supporting shoulders 18, preferably formed by suitably stamping or indenting the material of the standard, as clearly shown in Figs. 7 and 8. The standard 17 is formed in its relatively inner wall with a series of perforations 19, respectively arranged in transverse alignment with the shoulders 18 when the standards are in operative position. The standards 16 and 17 are preferably of hollow construction, to afford lightness, and the standard 16 is made in two sections by a transverse division below the shoulders 18, the sections being 85 connected by a hinge connection 20 on the relatively outer wall of the standard, and maintained in aligned or vertical position by a gravity latch 21, slidably mounted on the relatively inner wall of the upper section and engaging a keeper 22 on the lower section, as 90 clearly shown in Figs. 2 and 9. The upper section of the standard 16 is thus adapted to be moved in a direction away from the standard 17, to permit removal or insertion of the roll carriers, as will presently appear.

A supporting rod 23 is arranged for removable connection with the respective standards, one end seating loosely on one of the shoulders 18, and the other end being preferably squared at 24 for insertion in one of the squared openings 19 in the standard 17. 95

25 represents what we term a roll carrier, comprising a sleeve-like body of a size to encircle the shaft 23 and of a length somewhat in excess of the desired width of the paper to be used. The carrier is interiorly provided with bearing blocks 26 recessed for the reception of balls, the relatively upper portion of the shaft 23 being 100 also recessed at 28 for the reception of the balls 27. The carrier is thus supported on the shaft for independent longitudinal movement, the mounting of the shaft 105

preventing revolution of the carrier, as will be evident. The respective ends of the carrier are formed at diametrically opposed points with integral eyes 29, preferably arranged at the extremity of the vertical diameter of the carrier, as clearly shown in Fig. 4.

Carrier arms 30 are arranged at each end of the carrier, being formed at the carrier end with ring members 31 of materially greater diameter than that of the carrier. The ring members are designed to be arranged 10 in alinement with the respective ends of the carrier, and are formed with diametrically opposed eyes 32 and 33 arranged in pairs, as shown, one eye of each pair being alined with one of the eyes 29 at each end of the carrier. The carrier and ring 31 are secured together 15 by a U-shaped key 34, the arms 35 of which are designed to be passed through the respectively alined eyes on the ring and carrier. The ring of each arm 30 is thus supported concentric with the carrier, and removably secured thereto through the medium of the key. The 20 arm 30 projects forwardly from each respective ring, being provided at its forward or free end with a clamping member 36 to provide for removable attachment of the arms to an appropriate part of the typewriter carriage or platen, whereby said arms, and thereby 25 the carrier may be moved simultaneously and coincidentally with the carriage or platen.

Hanger arms 37 depend from the respective rings 31, being of a length to receive and support roll shafts 39 and 40, for a purpose which will presently appear. The 30 shaft 39 is preferably projected beyond one of the arms 37 and squared, as at 41, for the reception of an operating hand, not shown, whereby said shaft may be manually operated as desired.

In use a roll of paper 42, of the desired width for the 35 typewriter, is supported upon the carrier 25, a roll of carbon paper 43 being supported upon the shaft 39, and a second roll of typewriter paper 44 supported upon the shaft 40. The standards are arranged to support the respective shafts and the holding plates 9 disposed to receive the typewriter. The arms 30 are connected at 40 appropriate points with the platen, and the ends of the typewriter papers, with the carbon strip interposed are passed beneath the platen in the usual manner. The typewriter is operated in the ordinary way, the revolution 45 of the platen serving to properly feed the respective sheets of paper from the rolls, and the longitudinal movement of the platen or carriage feeding the carrier and supported rolls of paper and carbon longitudinally of the attachment frame coincidently and identically 50 with the carriage movement. The paper is thus maintained at all times in proper alinement with the printing plane, and the operator is saved time incident to the removal of printed sheets and the insertion of others. If desired the rolls of typewriter paper may be perforated or scored transversely to provide for the ready separation, after printing, into sheets of the desired length. If a carbon duplicate is not desired either the upper or lower roll of typewriter paper may be used without regard to the other rolls, thereby providing a single copy 55 of the matter printed.

The frame of the attachment is readily collapsible for close storage when not desired for use, and the standard 60 may be broken at its hinge joint to provide for the

release of the shaft 23 when the insertion of additional paper is necessary.

The device as a whole provides a simple and effective means for maintaining a continuous supply of paper to a typewriting machine, the particular construction insuring an absolute alinement of the paper with the printing plane, and the convenient removal or insertion of additional rolls of the paper when desired. As the carbon strip is capable of continued reuse, provision is made, as previously described for the manual winding of said roll after use of the carbon, whereby the carbon strip is adapted for reuse as long as a clear impression is obtained.

While preferring the described details of construction shown and described it is obvious that various changes may be resorted to without departing from our invention, and we wish it distinctly understood that we contemplate, as within the spirit of our invention, all such changes and variations in construction and arrangement as may fall within the scope of the appended claims.

Having thus described the invention what is claimed as new, is:—

1. The combination with a typewriter, of a paper supplying attachment therefor, said attachment comprising a frame, a paper roll supported thereby, and holding strips projecting from the frame, said strips being formed with 90 sockets to receive the typewriter legs.

2. A paper supplying attachment for typewriters comprising a relatively fixed frame, a shaft removably supported thereby, a carrier directly supporting a paper roll and longitudinally movable on the shaft, and means depending from the carrier and removably connected therewith for supporting a plurality of paper rolls.

3. A paper supplying attachment for typewriters comprising a frame, a shaft removably supported thereby, a carrier surrounding the shaft, a ball bearing between the carrier and shaft, and arms removably connected with the respective ends of the carrier, said arms being provided with typewriter attaching means.

4. A paper supplying attachment for typewriters comprising a frame, a shaft removably secured on the frame 105 against rotation, a carrier enveloping the shaft, a ball bearing between the carrier and shaft, typewriter attaching arms, said arms being shaped at the ends adjacent the carrier to provide rings, and means for securing said rings concentric with and spaced from the surface of the 110 carrier.

5. A paper supplying attachment for typewriters comprising a frame, a shaft removably secured on the frame against rotation, a carrier enveloping the shaft, a ball bearing between the carrier and shaft, typewriter attaching arms, said arms being shaped at the ends adjacent the carrier to provide rings, said rings and carrier ends being formed with alined eyes, and keys engaging the respective 115 eyes to secure the arms and carrier together.

6. A paper supplying attachment for typewriters comprising base blocks, standards removably supported in the blocks, one of the standards comprising hinged sections, a tie frame uniting the blocks, holding strips formed to receive the typewriter and engaging the tie frame, a shaft supported in the standard, a carrier movable longitudinally of the shaft, and means for connecting the carrier with the typewriter.

In testimony whereof, we affix our signatures in presence of two witnesses.

MORTON C. BLEDSOE.
G. FREDK. BLUMENKAMP.
